UNITED STATES PATENT OFFICE.

CESARE BARBIERI, OF NEW YORK, N. Y., ASSIGNOR TO THE VORTEX MFG. CO., A CORPORATION OF ILLINOIS.

PAPER-CUP-FORMING MACHINE.

Application filed March 15, 1924. Serial No. 699,424.

This invention relates to an improved automatic flat paper cup forming machine wherein shaped paper cup blanks are automatically fed singly from a magazine into the field of operation of a gripping mechanism which acts to grip the blank and advance the same into a position wherein glue is applied to two surfaces of the blank prior to the operation of a plurality of consecutively acting folding and creasing mechanisms which serve to fold the body portion of the blank over on itself, bend and press a glued flap against one side of the body portion, and then fold a tip portion so that a glued face thereof is pressed against the other side of the body portion to form the completed flat paper cup which when formed is automatically delivered into a stacking magazine from beneath.

It is an object of this invention to provide a machine wherein blanks are automatically removed from a magazine, supplied with an adhesive and automatically folded to form flat cups which are delivered through the bottom of a second magazine in which the flat cups are stacked and elevated ready for removal through the top of the stacking magazine.

It is also an object of the invention to provide a cup making machine wherein formed glued cups are advanced beneath a stacking mechanism in which cups are stacked and the stack of cups elevated each time a cup is added to the bottom of the stack.

It is furthermore an object of this invention to provide a machine wherein a cup blank is adapted to be automatically fed between adhesive applying mechanisms which operate at predetermined times to apply adhesive to opposite surfaces of the blank before the blank is folded to form a flat cup and is transferred into a stacking magazine and elevated therein.

It is an important object of this invention to provide a flat cup forming machine of a simplified type wherein a shaped blank is automatically removed from a magazine and delivered to a gripping device to be centered upon a table to have adhesive applied to portions thereof after which the blank is automatically advanced over the table and formed into a flat paper cup before being delivered into the lower end of a stacking

magazine from the top of which the cup may be removed.

Other and further important objects of this invention will be apparent from the disclosures in the drawings and specification.

The invention (in a preferred form) is illustrated on the drawings and hereinafter more fully described.

On the drawings:

Figure 1 is a top plan view of a flat paper cup forming machine embodying the principles of this invention with parts broken away.

Figure 2 is a rear elevation taken on line 2—2 of Figure 1.

Figure 3 is a front elevation of the machine taken on line 3—3 of Figure 1.

Figure 4 is a fragmentary plan view with parts removed, taken on line 4—4 of Figure 3.

Figure 5 is an enlarged transverse detailed section taken on line 5—5 of Figure 1 with parts in elevation.

Figure 6 is a detail section taken on line 6—6 of Figure 5.

Figure 7 is a detail sectional view taken on line 7—7 of Figure 1.

Figure 8 is a fragmentary detail plan view taken on line 8—8 of Figure 3 with parts omitted.

Figure 9 is a detail section taken on line 9—9 of Figure 8.

Figure 10 is a transverse detail section taken on line 10—10 of Figure 4.

Figure 11 is a transverse detail section taken on line 11—11 of Figure 4.

Figure 12 is an enlarged fragmentary detail section taken on line 12—12 of Figure 1.

Figure 13 is a top plan view of the parts illustrated in Figure 12.

Figure 14 is an enlarged detailed section taken on line 14—14 of Figure 4.

Figure 15 is a fragmentary enlarged end elevation of the discharge end of the machine.

Figure 16 is an enlarged fragmentary detail view taken on line 16—16 of Figure 1.

Figure 17 is a fragmentary detail section taken on line 17—17 of Figure 15 with parts omitted and with parts shown in elevation.

Figure 18 is a detail section through the glue pot mechanism taken on line 18—18 of Figure 4.

Figure 19 is an enlarged fragmentary detail section taken on line 19-19 of Figure 1.

Figure 20 is an enlarged detail view taken on line 20-20 of Figure 15 with parts omitted.

Figure 21 is a detail elevation taken on line 21-21 of Figure 13 with parts omitted.

Figure 22 is a section taken on line 22-22 of Figure 21 with parts in elevation.

10 Figure 23 is a fragmentary view of the table taken on line 23-23 of Figure 4 with a cup blank in position and illustrating the preliminary folding operations in dotted lines.

15 Figure 24 is a fragmentary plan view of the table showing a cup blank in position ready for the first folding operation.

18 Figure 25 illustrates the cup blank in an advanced position after the glue has been applied and with the lateral margin under process of being creased and bent upwardly.

20 Figure 26 illustrates the creased margin folded over and glued against the body of the cup.

25 Figure 27 illustrates the folded cup in a further position of advancement with the tip in place ready to be bent over.

30 Figure 28 illustrates the cup with the tip bent over and the cup ready to be advanced to cause the tip to be folded over and glued against the body of the cup.

Figure 29 is a plan view of the completed flat paper cup.

As shown on the drawings:

35 The reference numeral 1 indicates a machine frame having journaled thereon in suitable bearings a main driving shaft 2 one end of which is connected to be driven from any suitable source of power. Fixed on the

40 drive shaft 2 is a sprocket gear around which a drive chain 3 is trained. The chain 3 is also trained over a sprocket wheel 4 mounted on the hub sleeve 5 of a clutch housing 6. The clutch housing 6 is connected to be rotated by the sprocket wheel 4 by means of a pin 7 (Figure 5). The housing sleeve 5 is rotatable on a sleeve 8 which is free on a

45 shaft 9 journaled in frame bearings 10 and 11. Keyed on the sleeve 8 is a yoke 12 to which a pair of arms 13 are pivoted. The arms 13 are directed on opposite sides of the shaft 9 and carry pins 14 which project inwardly toward the sleeve 8 and are positioned between the yoke 12 and the beveled

50 inner end of a collar 15. The collar 15 is free on a flanged retaining sleeve 16 secured on the shaft 9 to the outside of the sleeve 8 and abutting the same. The clutch arms 13 have the outer ends thereof connected to

55 brake bands 17 positioned within the clutch housing 6.

Integrally formed on the inner end of the sleeve 8 is a disk 18 having a radial slot 19 in the inner surface thereof. The rounded end of a latch pin 20 projects into

the slot 19. The latch pin 20 is slidable in the hub of a hand wheel 21 which is keyed on the shaft 9 adjacent the disk 18. A pin 22 fixed in the hub of the hand wheel 21 projects into an arc shaped slot in the disk 18. A coiled spring 23 is engaged around the hand wheel hub between the hand wheel web and the disk 18. The hub of the hand wheel is provided with a reduced hub extension 24 which abuts against the end of the bearing 10 (Figure 5). Loosely engaged on the hand wheel hub extension 24 is a ring 25 which is integrally formed on the upper end of the long arm 26 of a throw out bell crank pivoted on a stud 27 supported on the machine frame. The throw out bell crank has a short arm 28 in the end of which a screw 29 is adjustably engaged to co-act with the short arm 30 of a power throw in or starting bell crank which is secured on a starting shaft 31 supported in suitable bearings on the machine frame 1. A handle or lever 32 is connected to operate the starting shaft 31. The starting bell crank has a long arm 33 the upper end of which is U-shaped or forked and carries pins 34 which project into a groove 35 provided in the shiftable collar 15 (Figure 16).

Referring now to the blank feed magazine and feeding mechanism a gear 36 is fixed on the clutch carrying shaft 9 and meshes with a large gear 37 fixed on a shaft 38 journaled in bearings formed on the machine frame.

Fixed on the inner end of the shaft 38 is a beveled gear 39 which is in mesh with a beveled gear 40. Secured on the shaft 38 adjacent the beveled gear 39 is a gear 41 which meshes with a gear 42. The gear 42 is mounted on a feed shaft 43 which is journaled in bearings provided in a magazine base section 44 supported on the frame 1.

A blank feed reel 45 is mounted on the shaft 43 within the base section 44. Secured upon the magazine base section 44 is a sector-shaped cup blank holder 46 having a blank outlet slot 47 therein (Figure 7). Blank guide posts 48 are mounted upon the holder 46.

Supported in the magazine base section 44 is a bracket 49 supporting an adjustable bar 50 carrying a pin 51 which projects upwardly into the cup blank holder 46 to afford a support for the stack of cup blanks within the magazine. Rubber covered pads 52 form part of the feed reel and are arranged to operate on a paper blank to feed the same forwardly out of the magazine only at a predetermined time.

Mounted on the front end of the shaft 38 is a wheel or disk 53 having an eccentric pin 54 thereon on which one end of an eccentric rod or bar 55 is engaged. The eccentric bar 55 is pivotally supported near its other end on a pin 56 carried on the lower end of a link 57 which is fixed on a pin 58

115 carried by a slidable block 59. The block 59

is slidable in a slot 60 provided in the front of the machine frame 1 (Figure 3). Integral- 5 ly formed at an angle on the bar 55 is an extension arm 61. The bar 55 and the arm 61 form a bell crank member. Pivotally connected to the end of the arm 61 is one end of a connecting rod 62 the other end being pivotally connected to the upper end of the outer arm of a double arm lever 63. The 10 lower end of the lever 63 is pivoted on a bracket 64 secured on the machine frame 1.

Secured to the slidable block 59 is a horizontal bar 65 which is slidable beneath a guide or retaining plate 66 secured to the 15 machine frame 1. Secured to the slidable bar 65 is a bracket 67 on which a projecting arm 68 is supported. A blank advancing plate 69 is fixed beneath the projecting arm 68 and extends into the path of the advancing cup blanks. Fixed on the top of the arm 68 is a carriage 70 having an upper gripper arm 71 integrally formed thereon which carries a rocker pad or upper gripper jaw 72. Secured to the carriage 70 is a plate 73 de- 20 flected at 74. A cup blank centering flange 75 is formed on one end of the carriage plate 73.

Fixed on the inner end of the pin 58 is the upper end of a link 76 the lower end of 30 which is connected to one end of a connecting bar 77 (Figure 9). The other end of the connecting bar 77 is connected to one arm of a bell crank 78 which is pivoted on the bracket 67. Fulcrumed on the other arm of 35 the bell crank 78 is a lower gripper bar 79 one end of which is pivoted on the bracket 67. The other end of the lower gripper bar 79 has a gripping anvil or lower jaw 80 supported thereon for co-action with the upper gripper jaw 72.

When a cup blank 90 (Figure 24) is fed out of the bottom of the cup blank holding magazine through the slot 47 the blank 90 is delivered onto a stationary table 81 45 having a raised portion 82 provided with a curved stop edge 83. A stationary table section 84 is provided in the plane of the table 81 and is separated therefrom by a diagonal opening or slot 85 in which a pair 50 of upper and lower blank folding bars 86 and 87 are adapted to move in a vertical plane. The bars 83 and 87 are separated by a slot 88 and at one end rest on one another and are supported upon the top of a vertically 55 slidable bracket 89 mounted in guides on the machine frame 1.

The disk 53 when rotating actuates the rod 55 which acts to slide the block 59 toward the cup blank magazine thereby caus- 60 ing the link or crank 76 to operate the bar 77 and the bell crank 78, to move the lower gripping jaw 80 into open position to permit the advance end of the delivered cup blank 90 to engage between the gripper jaws 72 65 and 80. With the continued operation of

the disk 53 the lower gripper jaw 80 is closed to clamp the cup blank 90 which is carried over the table 81—84 into the position illus- 70 trated in Figure 24 over the top of the upper folding bar 86 and with one portion of the cup blank 90 over an aperture 91 in the table section 81 (Figure 4). The table section 81 has a corner thereof positioned above one end of a glue tank or trough 92 which is mounted transversely of the machine frame. 75 The glue trough 92 has a pair of spaced bearing lugs 93 formed on the outer end thereof. Rotatable in the bearing lugs 93 is a short shaft 94 on which a bracket or elbow 95 is fixed between the lugs 93. Attached to the 80 elbow 95 within the trough 92 is a lever or arm 96 having a glue applying pin 97 thereon. The shaft 94 has a head 98 formed on one end thereof to which one end of a coiled spring 99 is secured. The spring 99 is coiled around the shaft 94 and has the other end connected to the bearing shank 100 of a crank 101. The crank 101 has a rocker head 102 (Figure 18) the curved surface of which rests upon the upper end of a vertically slid- 85 able offset bar 103 which is slidable in a guide groove in a middle bearing arm or bracket 104 three of which are secured on the rear side of the machine frame 1. A roller 105 is mounted on the slidable bar 103 and co-acts with a cam 106 which is fixed on a main cam shaft 107 journaled in the bearing arms 104. A dab or spot of glue 108 is adapted to be applied to the under surface 90 of the cup blank 90 by the pin 97 which is projected upwardly through the table aperture 91 into contact with the blank.

With the gripper jaws 72 and 80 in their advance position ready to grip the next cup blank the blank feed plate 69 is in its advance position over the cup blank 90 as illus- 105 trated in Figure 24 with one edge of the plate 69 above the edge of the table 81 which forms one side of the opening 85. Just previous to the time that the gripper car- 110 riage starts to move away from the cup blank magazine the blank folding bars 86 and 87 are raised thereby bending up the blank position 109 into the position shown in Figure 25. The other portion 110 of the cup blank is held in place by the feed plate 69. Pivotally attached to the slidable bracket 89 is the upper end of a link 111 (Figure 11) the lower end of which is pivoted to a curved arm 112. One end of the arm 112 is pivoted 115 on the frame 1, while the other end carries a roller 113 disposed in a cam groove 114 to co-act with a cam 115. The cam 115 is formed on one side of a double cam wheel or disk 116 which is fixed on the cam shaft 107. 120

As the carriage moves back the grippers first close and grip the next blank while the blank feed plate 69 moves over the table and through the slot 88 between the elevated bars 125 130

86 and 87 thereby causing the upturned portion 109 of the first blank to be folded over against the top surface of the feed plate 69 as the partially folded blank is advanced 5 over the table section 84 and over a longitudinal slot 117 provided in the table section. As the partially folded blank is advanced over the table section 84 a portion of the blank passes beneath the rounded creasing 10 head 118 of a creasing lever 119. A crease 120 (Figure 25) is thus made in the advancing cup blank thereby forming a flap section 121 which is slightly bent upwardly as the blank is advanced to cause the flap 121 to 15 ride over an inclined surface of a shoe 122, (Figure 4) on the table section 84.

As the partially folded cup blank is advanced by the feed plate 69 from the position illustrated in Figure 24 into the position shown in Figure 25 a second glue applying mechanism acts automatically to apply a strip of glue on the upper surface of the cup blank flap 121 being formed. The second glue applying mechanism comprises a glue 20 tank or trough 123 supported longitudinally of the machine upon a bracket or post 124 slidable in the machine frame 1. The glue tank 123 has a glue outlet aperture 125 in the bottom thereof. Rotatably supported 25 on the bottom of the glue tank 123 below the aperture 125 is a glue applying disk or wheel 126 supported on a shaft 127 on the other end of which a small gear or pinion 128 is fixed. The pinion 128 meshes with a 30 larger gear 129 rotatably mounted on the side of the glue tank 123. Meshing with the large gear 129 is a pinion 130 mounted on one end of a shaft 131 journalled transversely of an extension 132 on the glue tank. 35 A pinion 133 is mounted on the other end of the shaft 131 and is in mesh with a gear 134 mounted on a shaft 135 supported in a stationary bearing 136. A gear 137 is fixed on the other end of the shaft 135 and meshes with 40 a gear 138 on the rear end of a shaft 139 journalled in a bearing 140 on the machine frame. A cup feed cam 141 is fixed on the other end of the shaft 139. The gear 138 also meshes with a gear 142 rotatable on the 45 machine frame and receiving a drive from a gear 143. The gear 143 is fixed on a rotatable shaft 144 on the front end of which a lower cup feed roll 145 is mounted. The gear 143 meshes with and receives a drive 50 from a large gear 146 which is mounted on a shaft 147 journalled in a bearing in the machine frame. A bevel gear 148 is fixed on the shaft 147 to the outside of the large gear 146. The bevel gear 148 is in mesh with 55 a bevel drive gear 149 fixed on the end of the cam shaft 107. An upper cup feed roll 150 is positioned on the front end of a shaft 151 journalled in a bearing 152 and co-acts with the lower cup feed roll 145. A gear 153 is 60 fixed on the rear end of the shaft 151 and

meshes with the gear 143 to receive a drive therefrom.

Referring now to Figure 10 we have to consider the mechanism for raising and lowering the glue tank 123. Pivoted to a web or 70 rib 154 on the slidable post 124 is the upper end of a link 155 the lower end of which is pivotally connected to a curved arm 156. One end of the curved arm 156 is pivoted to the machine frame 1 while the other end carries a roller 157 disposed in a cam groove 158 to co-act with a cam 159 formed within the cam disk 116. The glue tank 123 is vertically adjustable on the reciprocating 75 bar 124 and is provided with an adjusting screw 160 to hold the glue tank in a set position with respect to the bar 124.

A flap folding mechanism is provided for folding the cup flap 121 over against the cup side 109 after the strip of glue has been applied to the flap 121 by the glue applying wheel or disk 126 and after the flap has been partially bent upwardly by passing over the inclined surface of the shoe 122 and over an inclined plate 161 (Figure 4). Fixed on the cam shaft 107 is a cam 162 with which a roller 163 co-acts. The roller 163 is carried on the short arm of a spring-controlled bell crank 164 which is pivoted on the machine frame 1 (Figure 14) and has a bearing block 165 in the yoked end 166 of the long arm thereof. A pin 167 is journalled in the bearing block 165 and is connected to a carriage 168 which is slidable on a support 169 on the machine frame. Secured to the slidable carriage 168 is a flap folding plate 170 which is adapted to slide against the upturned flap 121 and fold the flap over against the body of the cup as illustrated in Figure 26.

The partially folded and formed cup is now in the position illustrated in Figure 27 partially positioned beneath a stationary retaining plate 171 located above the table section 84 as illustrated in Figure 1. The tip 172 of the cup projects over the inclined edge 173 of the table section 84 ready to be bent over at right angles to the body of the cup by a tip bending mechanism. Mounted on the shaft 147 to the inside of the gear 146 is a cam 173 with which a roller 174 co-acts. The roller 174 is mounted on the short arm of a bell crank 175 which is pivotally supported on a bracket 176 formed on the machine frame. Pivotally connected to the end of the long arm of the bell crank 175 is the lower end of a rod or post 177 which projects upwardly through a boring 178 having a spring 179 therein which is coiled around the rod 177 and acts to hold the rod in its lower restricted position with the roller 174 in contact with the cam 173 (Figure 17). Secured on the upper end of the rod 177 is a block 180 which is recessed to receive a plate 181. The plate 181 is rigidly secured 100 105 110 115 120 125 130

- to the block 180 and has a cup tip bending shoe or pad 182 integrally formed thereon and having an inclined edge 183 parallel to the table edge 173. Secured on the plate 181 5 is a block 184 having a recess 185 and guide openings therein. Guide rods 186 project through the opening in the block 184 and have a rectangular plate or cup clamping pad 187 secured to the lower ends thereof. 10 A coiled spring 188^a seats in the block recess 185 (Figure 22) and against the pad 187 to hold the same resiliently against the cup tip bending shoe 183. When the cam 173 reaches a certain position of rotation with 15 respect to the roller 174 the spring 179 is permitted to act to slide the rod 177 downwardly thereby lowering the shoe 183 against the cup tip 172 (Figure 28) while the pad 187 seats against the top surface of the flat 20 cup to hold the cup clamped between the table section 84 and the pad 187 while the shoe 182 bends the cup tip 172 downwardly at right angles as illustrated in dotted lines in Figure 21.
- 25 At this stage of the forming of the flat cup the feed cam 141 comes into contact with the cup and feeds the same forwardly over a pair of table rolls 188 and between the shoe 182 and the pad 187. As the cup is advanced by the feed cam 141 the cup feed plate 69 starts to move out of the cup toward the cup blank holding magazine. The rolls 188 are rotatably supported beneath the table section 84 and project through openings in the table to afford a rolling support for the cup as it is advanced by the feed cam 141. With the advance of the cup from the position shown in Figure 28 to the dotted line position of Figure 21 the tip 172 is bent 30 upwardly against the underside of the body of the cup so that the spot of glue 108 acts to glue the tip 172 to the body of the cup thereby completing the forming of the cup 35 (Figure 29).
- 40 The formed cup is advanced by the feed cam 141 between the feed rollers 145 and 150 which press the glued parts together and at the same time advance the cup over onto the table extension 189. Secured on the end 45 of the machine frame 1 is a casting 190 having an extending arm 191 on which a carriage 192 is slidably engaged. A stop 193 is fixed on the end of the arm 191. The carriage 192 is provided with a vertical slot in 50 which a plate 194 is slidably engaged. Integrally formed at right angles to the upper edge of the slide plate 194 is a horizontal plate 195 which extends transversely beneath the table extension 189. Secured to the bracket plate 195 on opposite sides of the table extension 189 are a pair of slide bars 196 recessed at 197 leaving upturned hooks or fingers 198. The hooks are slightly 55 curved to conform to the curvature of the curved open end of the flat cup. A cup
- 60 pocket is thus provided in the slideable cup removing bars 196 which slide between guides 199 and 200 fastened to the casting 190. Mounted upon the guides 199 and 200 is a cup holding and stacking magazine base 65 section 201 having a substantially triangular shape as illustrated in Figure 1 and having guide slots 202 therein (Figure 19) through which the bars 196 are adapted to slide and be raised. Secured to the magazine base 70 section 201 are a plurality of upright posts 203 supporting an upper magazine section 204 similar in shape to the lower section 201. Secured to the inner surface of the lower 75 magazine base section 201 and extending upwardly through the upper magazine section 204 are a plurality of flexible slats or cup retaining springs 205 over which a cup carton is adapted to be engaged so that a stack of 80 flat cups may be delivered upwardly into the carton. The slide plate 194 is provided with a slot 206 (Figure 20) through which a stub shaft 207 projects. The shaft 207 is supported in a bearing 208 formed on the carriage 192. Secured on the outer end of the stub shaft 207 is a bell crank 209 having a cam block 210 engaged on the inner side of the short arm of the bell crank. The bell 85 crank block 210 projects into the slide plate slot 206 (Figure 20) to permit raising and lowering of the slide plate 194 with respect to the carriage 192. The long arm of the bell crank 209 is pivotally connected to one end of a link 211. The other end of the link 211 is pivoted to the inner arm of the double 90 arm lever 63. The bars 196 are first advanced toward the feed rolls 145 and 150 to permit the formed flat cup to drop into the bar recesses 197 after which the bars are raised and then retracted to deliver the cup 95 in the stacking magazine underneath the stack of cups already formed.
- 100 The operation is as follows:
- A stack of cup blanks 90, shaped as illustrated in Figure 24, are placed between the 105 magazine guide posts 48 with the lowermost blanks disposed within the magazine base 46. The lowermost blank 90 within the magazine rests upon the pin 51 and upon the spaced disks of the blank feed roll 45.
- 110 The main drive shaft 2 is connected to be rotated from any suitable source of power and drives the clutch housing 6 by means of the chain 3 and the sprocket gear 4. The machine is provided with the starting handle 32 which when operated rocks the shaft 31 thereby causing the control bell crank 30—33 to operate. The long arm 33 of said bell crank (Figure 16) thus shifts the collar 15 inwardly. The clutch arms 13 thus actuate the brake bands 17 thereby imparting a drive to the sleeve 8 and the hand wheel 21 through the pins 20 and 22 (Figure 5). The hand wheel 21 being keyed on the shaft 9 rotates the same and a drive is imparted 120
- 125 to the sleeve 8 and the hand wheel 21 through the pins 20 and 22 (Figure 5). The hand wheel 21 being keyed on the shaft 9 rotates the same and a drive is imparted 130

to the gears 36, 37, 41 and 42. The feed roll shaft 43 and the blank feed roll 45 are thus rotated. At a predetermined time in each revolution of the feed roll 45 the rubber 5 covered pads 52 are brought into contact with the lowermost cup blank in the magazine. The pads 52 act to feed the lowermost cup blank out of the magazine base section 46 through the outlet slot 47. The 10 supporting pin 51 (Figure 7) cuts through the edge of the cup blank as it is fed forwardly out of the magazine onto the raised table portion 82. As the lowermost cup blank is delivered from the magazine the 15 remaining cup blanks drop by gravity.

With the delivery of a cup blank from the magazine the disk 53 actuates the eccentric bar 55 and the links 57 and 76. The connecting bar 77 and the bell crank 78 thus 20 actuate the lower gripper bar 79 to move the lower gripper jaw 80 into open position. The eccentric bar also serves to advance the carriage 70 toward the magazine 46 so that the open gripping jaws 72 and 80 are 25 respectively positioned over and below the advance portion of the delivered cup blank.

With the next half revolution of the disk 53 the lower gripper jaw 80 is first moved upwardly into closed position to clamp the 30 cup blank between the jaws 72 and 80 after which the carriage 70 starts to move away from the magazine 46. The cup blank is thus pulled off of the raised table portion 82 and is advanced over the table sections 35 81 and 84 and over the lowered bending bar 86 into the position illustrated in Figure 24 the rear curved edge of the cup blank dropping upon the table section 81 when the curved edge 83 of the raised table plate 40 82 is passed.

The blank gripping jaws are again opened with the next half revolution of the disk 53 and the advanced blank is released as the carriage 70 starts back for the next cup 45 blank. The cup feeder plate 69 on the carriage 70 is thus moved over the advanced cup blank 90 into the position shown in Figure 24 with the cup blank portion 110 between the table section 81 and the feed 50 plate 69. The flange 75 on the carriage acts against the edge of the advanced cup blank and pushes the cup blank back against the edge 83 of the table plate 82. The cup blank is thus properly centered.

55 The cam 106 (Figure 18) on the cam shaft 107 now acting on the roller 105 raises the slide bar 103 thereby operating the crank 101 causing the arm 96 to swing upwardly in the glue tank 92. The glue applying pin 60 97 is thus projected through the table aperture 91 and acts to apply a dab of glue 108 to the under surface of the advanced cup blank.

65 After the dab of glue 108 has been applied to the cup blank the cam 115 (Figure 11) on

the cam shaft 107 co-acts with the roller 113 in the cam slot 114 to raise the bracket 89 thereby causing the two arms 86 and 87 to be lifted from the full line position of Figure 23 upwardly to the dotted line position. 70 The portion 109 of the cup blank is thus bent upwardly by the upper bar 86 into the position illustrated in Figure 25.

The carriage 70 again starts to return after another blank delivered from the magazine 46 has been gripped by the gripper jaws 72 and 80. With the return of the carriage toward the discharge end of the machine the feed plate 69 acts to move against the upturned portion 109 of the cup blank thereby forcing the cup blank to pass through the slot 88 between the raised arms 86 and 87. The cup blank portion 109 is thus bent over against the cup blank portion 110 with the feed plate 69 still between the cup sections 109 and 110 creasing the cup blank along the inclined edge of the feed plate.

When the cup blank is advanced from the position illustrated in Figure 24 the roller 157 acting in the cam groove 158 (Figure 10) causes the bracket 124 to be lowered thereby bringing the glue applying disk 126 into contact with the upper surface of the marginal portion 212 of the cup blank. Glue from the tank 123 flows through the aperture 125 onto the peripheral surface of the disk 126. The disk 126 is rotated by means of the meshing gears 128, 129 and 130 and by the gears 133, 134, 137, 138, 142, 143 and 146 from the bevel gear 148 which in turn receives a drive from the bevel gear 149 on the cam shaft 107. After a strip of glue has been applied to the portion 212 of the cup blank the roller 157 co-acting with the cam groove 158 and the members 155 and 156 causes the glue tank 123 to be raised lifting the glue applying disk 126 out of engagement with the cup blank.

As the cup blank is being folded by passing through the slot 88 between the raised arms 86 and 87, the advance end of the cup blank passes beneath the rounded head 118 (Figure 7) on the creasing arm 119 and over the slot 117. The creaser head 118 thus acts to crease the advancing cup blank along the line 120 (Figure 25) to form the flap 121. With the continued advance of the cup blank by the feed plate 69 the creased flap 121 passes over the inclined surface of the shoe 122 and then over the inclined plate 161, (Figure 4). The flap 121 is thus bent upwardly along the crease 120 as the feed plate advances the partially formed cup over the table section 84.

As the flap 121 is bent up the cam 162 on the cam shaft 107 acting on the roller 163 actuates the bell crank 164 to move the carriage 168 toward the table 84 into the

position illustrated in Figure 14. The flap folding plate 170 thus folds the flap 121 over against the cup section 109 thereby causing the glued surface of said flap to adhere to the cup section 109 (Figure 26). The partially formed cup is further advanced by the feed plate 69 into the position shown in Figure 27 wherein the tip portion 172 of the cup projects over the edge 173 of the table section 84.

The cam 173 (Figure 17) now comes into play and acting on the roller 174 swings the bell crank 175 downwardly against the action of the spring 179. The post 177 is thus pulled downwardly thereby causing the cup tip bending shoe 182 to move from the full line position of Figure 21 to the dotted line bending the cup tip 172 downwardly at right angles while the spring controlled pad 187 has one corner thereof engaging against the body of the cup. The body of the cup is thus clamped between the table 84 and the pad 187 while the tip 172 is being bent over (Figures 27 and 28). At this stage in the operation the gripper carriage 70 starts again to move toward the magazine 46 thereby causing the cup feed plate 69 to move out of the partially folded cup. Just about this time in the operation the cup feed cam 141 on the shaft 139 is rotated to engage the top surface of the flat cup and advance the same over the table rollers 188 between the cup feeding or advancing rolls 145 and 150. As the cup is moved from the dotted line position shown in Figure 21 the bent over tip 172 is bent upwardly against the under side of the flat cup so that the dab of glue 108 will cause the tip to adhere to the body of the flat cup (Figure 29) to form the completed flat cup.

The cup feed rolls 145 and 150 which are rotated from the gear mechanisms connected with the cam shaft 107, now act to advance the completed flat cup over onto the table extension 189 to drop by gravity into the pocket 197 of the cup removing bars 196. The bars 196 are advanced toward the rollers 145 and 150 by the carriage 192 which is slideable on the guide bar 191 by the action of the inner lever arm 63 and the link 211 which are connected by the connecting rod 62 to the end of the arm 61 on the eccentric bar 55 (Figure 3). When the carriage 192 starts to move outwardly toward the cup stacking end of the machine the bell crank 209 is first actuated to swing the short arm of the bell crank 209 upwardly so that the block 210 (Figure 20) acts to raise the plate 194 thereby elevating the bars 196. These bars being positioned beneath the cup stacking magazine 201 act to raise the stack of formed cups already stacked within the stacking magazine. As the carriage 192 moves outwardly the raised bars 196 slide

from under the raised stack of cups carrying a formed cup in the pocket 197 into the base section 201 of the stacking magazine beneath the stack of cups already stacked therein. The stack of cups in the stacking magazine drop into the pocket 197 upon the cup just delivered and the bars 196 are again lowered as the carriage 192 reaches the end of its outward movement on the bar 191.

The flat cups being formed follow one another in a constant stream through the machine and are automatically delivered one at a time into the bottom of the stacking magazine and are elevated each time a new cup is added to the bottom of the stack. The flat cups thus pile up in the stacking magazine between the flexible guides or springs 205 ready to be lifted in any desired quantities from the top of the stacking magazine.

A cup carton may be engaged over the upwardly projecting ends of the spring guides 205 with the open end of the carton resting on the upper magazine section 204 so that a stack of flat cups may be pushed upwardly into the carton and the carton removed from the spring guides.

If at any time during the operation of the machine cup blanks or partially formed cups should become clogged there will be a tendency for the shaft 9 (Figure 5) to slow up so that a relative movement will take place between the hand wheel 21 and the disc 18. When this occurs the control pin 20 is forced away from the disk 18 through the hand wheel hub and against the ring 25 on the long arm 26 of the release bell crank 26-28 (Figure 16). The short arm 28 of the bell crank is thus swung upwardly so that the adjustable screw 29 will act against the short arm of the starting bell crank 30 to throw the same out of active position. The clutch collar 15 is thus moved outwardly to release the clutch drive and the machine is automatically stopped.

If at any time during the operating of the machine, it may be desired to quickly stop the machine the hand wheel 21 may be manually turned to cause the control pin 20 to release the clutch drive. The machine of course may be started and stopped by operating the control handle 32 on the shaft 31.

I am aware that numerous details of construction may be varied through a wide range without departing from the principles of this invention, and I therefore do not purpose limiting the patent granted, otherwise than necessitated by the prior art.

I claim as my invention:

1. A flat cup forming machine comprising a blank holding magazine, means for automatically removing a cup blank from the magazine, devices for folding and sealing

portions of the blank to form a collapsed cup, means for transferring the cup through the machine from one of said devices to the other, a stacking device, and means for delivering the cup into the bottom of the stacking device.

2. A flat cup forming machine comprising a blank holding magazine, means for automatically removing cup blanks one at a time from the magazine, a table, a gripper device for engaging a blank and drawing the same over the table into a centered position, a blank feed plate adapted to move over the centered cup blank, means for applying a dab of glue to the bottom surface of the cup blank, a cam operated slotted device acting through the table to bend a portion of the blank upwardly, means for moving the feed plate through the slotted device to fold the upturned portion of the blank over against the feed plate, means for applying a strip of glue to one marginal portion of the cup blank, a creasing device for impressing a crease in the cup blank to form a flap of said marginal portion, inclined members over which the flap rides to cause the flap to be turned up, a member slidable transversely of the table to fold the glued upturned flap over against the body of the cup, vertically acting means for bending over a tip portion of the partially formed cup, and a feed cam for engaging the partially formed cup to advance the same and cause the bent over tip to be folded against the body of the cup with the dab of glue positioned to hold the tip glued in place.

3. A flat cup forming machine comprising a blank holding magazine, a cup stacking magazine, means for automatically removing a cup blank from the blank holding magazine, and a plurality of mechanisms adapted to act successively on the blank to first glue and fold the same into a flat cup and then automatically deliver the completed flat cup into the bottom of the stacking magazine.

4. In a flat cup forming machine a cup blank holding magazine, a table having an aperture therein, means for removing a cup blank from the magazine and delivering the same on the table over said aperture, a glue tank, a pin therein, and a cam mechanism adapted to move the pin upwardly through the table aperture to apply a dab of glue in a predetermined position on the centered cup blank.

5. In a flat cup forming machine a table having an aperture therein, a blank holding magazine, means for delivering a cup blank from the magazine onto the table over the aperture, a glue tank, an arm pivoted in the tank, a pin on said arm, a slidable member, a roller thereon, and a cam co-acting with the roller to operate the slidable member and the pivoted arm to cause the pin to be pro-

jected through the table aperture to apply a dab of glue on the cup blank.

6. In a flat cup forming machine, a table, a blank holding magazine, means for removing a cup blank from the magazine and delivering the same on said table, a reciprocating carriage, a plate on said carriage adapted to move over the cup blank, and a slotted device adapted to move through the table to bend the cup blank and permit the plate to carry the cup blank through the slotted device to fold the cup blank over against said plate.

7. In a flat cup forming machine a table, a carriage, means for reciprocating the carriage, gripper means on one end of the carriage for engaging and drawing a cup blank onto the table, a centering means on the other end of the carriage for moving the cup blank into a centered position on the table, means for applying glue to portions of the cup blank, a plurality of consecutively acting folding mechanisms, and a plate on said carriage adapted to be moved into a position over the cup blank and then move the cup blank through the fields of operation of said folding mechanisms to have the cup blank folded into a flat cup.

8. In a flat cup forming machine, a slotted table, a carriage, means for delivering a cup blank on said table, a plate adapted to coat with said blank, means for applying a dab of adhesive to the cup blank, means for bending a portion of the cup blank upon the plate as the cup blank is advanced by said plate, a device for applying adhesive to a margin of the cup blank while it is being advanced, mechanisms for bending the adhesive margin over against the body of the cup being formed, and means for bending over the tip of the partially formed cup so that the dab of adhesive will hold the bent over tip secured in place to form a completed flat cup.

9. A flat cup forming machine comprising a slotted table, a carriage, a cup blank feed plate carried by the carriage, means acting upwardly through the slotted table to fold a portion of the cup blank, adhesive applying means for applying adhesive to portions of the cup blank as the cup blank is advanced over the table by said feed plate, means for turning up a margin of the advancing cup blank, a reciprocating plate for folding the turned up margin over against the body of the cup being formed, reciprocating means for bending over a tip portion of the cup, and mechanisms for advancing the partially formed cup to fold over the bent tip to form the completed flat cup.

10. A flat cup forming machine comprising a slotted table, a carriage, a cup blank feed plate carried by the carriage, a cam shaft, a cam thereon, means operated by the cam to move through the slotted table to

- fold a portion of the cup blank, an adhesive applying mechanism, a cam on the cam shaft for operating the same to cause a dab of adhesive to be applied to the centered cup blank, a second adhesive applying mechanism, a cam on the cam shaft, mechanisms operated thereby to cause the second adhesive applying mechanism to apply adhesive to a margin of the cup blank, means 5 for turning up the adhesive margin of the cup blank as the cup blank is advanced over the table by said feed plate, a reciprocating plate for folding the turned up margin over against the body of the cup being formed, 10 a cam on said crank shaft for operating the reciprocating plate, means for folding over the tip portion of the cup being formed, a cam mechanism for operating the same, and means operated from the cam shaft for 15 feeding the finished flat cup from the machine.
11. A flat cup forming machine comprising a table, means for automatically delivering a cup blank onto the table, a reciprocating feed plate for advancing the cup blank, a cam shaft, means for operating the cam shaft and said blank delivering means, a plurality of adhesive applying mechanisms, 20 cam operated mechanisms operated from the cam shaft for operating the adhesive applying mechanisms, and a plurality of mechanisms operated from the cam shaft for folding the cup blank into a flat cup.
12. A flat cup forming machine comprising a table, a plate for advancing a cup blank over the table, a plurality of adhesive applying and folding mechanisms, cams for operating the same, and a shaft supporting and driving all of said cams.
13. A flat cup forming machine comprising a table, a plate for advancing a cup blank over the table, adhesive applying mechanisms, cams for operating the same, a plurality of blank folding devices, cams for operating said devices, a cam shaft supporting all of said cams, and means for operating the cam shaft.
14. In a flat cup forming machine the combination with a table, of a cup blank feeding device for advancing a cup blank over the table, a plurality of adhesive applying mechanisms, cams for operating said mechanisms, a cam shaft supporting said cams, and means for operating the cam shaft and said cup blank feeding device.
15. In a flat cup forming machine the combination with a table, of a cup blank feeding device for advancing a cup blank over the table, a plurality of devices for 50 folding the cup blank into a flat cup as it is being advanced, cams for operating said folding devices, a cam shaft supporting said cams, and means for operating the cam shaft and said cup blank feeding device.
16. In a flat cup forming machine the combination with a table, of a cup blank feeding plate for advancing a cup blank over the table, cam operated mechanisms for folding the cup blank around said feed plate to form a flat cup, a cam for continuing to advance 70 the flat cup over the table when the feed plate is retracted from the flat cup, and a pair of feed rolls for engaging and delivering the completed cup from the machine.
17. In a flat cup forming machine the combination with a table, of means for advancing a cup blank over the table, means for folding over a portion of the cup blank, means for applying adhesive to the unfolded portion of the cup blank, means for turning up an adhesive portion of the unfolded portion of said cup blank, a reciprocating device for folding down the upturned adhesive portion against the first folded portion, a reciprocating mechanism for bending 85 over a tip portion of the partially formed cup, means for advancing the partially formed cup to cause the tip portion to be folded against the body of the cup, and means for engaging and advancing the 90 formed cup and pressing the folded over portions thereof.
18. In a flat cup forming machine the combination with a table, of means for advancing a cup blank over the table, means for applying adhesive to portions of the cup blank, mechanisms for folding the cup blank to form a flat cup, and a cam roller for engaging and advancing the formed cup after the forming thereof.
19. In a flat cup forming machine the combination with a table, of means for advancing a cup blank over the table, means for applying adhesive to the cup blank, mechanisms for folding the cup blank to 105 form a flat cup, a pair of feed rollers, and a cam roller adapted to engage the formed cup and advance the same between the feed rollers for delivery from the machine.
20. In a flat cup forming machine the combination with a support, of means for advancing a cup blank over the support, a cup blank folding device, a glue applying mechanism, and a double cam mechanism for operating the folding device and said 115 glue applying mechanism.
21. In a flat cup forming machine the combination with a support, of means for advancing a cup blank over the support, a cup blank folding device, a glue applying 120 mechanism, and cam operated means for intermittently reciprocating the folding device and said glue applying mechanism.
22. In a cup forming machine the combination with a slotted table, of means for advancing a cup blank onto the table, a folding device, a pivoted arm, a link connecting said arm with said folding device, and a 125

cam mechanism for operating the arm and link to cause the folding device to operate to fold a portion of the cup blank.

23. In a cup forming machine the combination with a slotted table, of means for advancing a cup blank onto the table, a folding device adapted to act through the slotted table, a pivoted arm, a link connecting the folding device with said arm, a rotatable member having a cam groove therein, a roller on said arm positioned to run in said cam groove, and means for operating said rotatable member to cause the folding device to fold a portion of the cup blank.

24. In a cup forming machine the combination with a table, of means for advancing a cup blank onto the table, a glue applying device, a pivoted arm, a link connecting the glue applying device with said arm, a rotatable member having a cam groove therein, a roller on said arm positioned to run in said cam groove, a means for operating said rotatable member to cause the glue applying device to be lowered at a predetermined time to apply glue to the cup blank.

25. In a cup forming machine the combination with a table, of means for advancing a cup blank onto the table, a glue tank, a glue applying disk carried thereby, means for rotating the disk, a pivoted arm, a link connecting the arm to said tank, a rotatable member having a cam groove therein, a roller on said arm adapted to travel in said cam groove, and means for operating said rotatable member to cause the glue tank and disk to be lowered at a predetermined time to cause the disk to apply glue to the cup blank.

26. In a flat cup forming machine the combination with a cup blank holding and delivering mechanism, of a flat cup stacking mechanism, and a plurality of devices disposed between the cup blank holding mechanism and the stacking mechanism adapted to form flat cups from the cup blanks, and advance the flat cups into the field of operation of the stacking mechanism.

27. In a flat cup forming machine the combination with a cup blank holding and delivering mechanism, of a flat cup stacking device, a plurality of mechanisms for forming flat cups from the cup blanks, a plurality of cam mechanisms for operating the forming mechanisms, a cam shaft for operating said cam mechanisms, and means for driving the cam shaft.

28. In a flat cup forming machine the combination with a cup blank holding and delivering mechanism, of a flat cup stacking device, a plurality of mechanisms for forming flat cups from the cup blanks, a plurality of cam operated mechanisms for actuating the forming mechanisms, a cam shaft for driving said cam operated mechanisms,

a driving device, a clutch mechanism between the cam shaft and said driving device, and means connected with the clutch mechanism for automatically throwing the clutch mechanism out when the machine becomes jammed.

29. In a cup forming machine the combination with a table having a slot therein, means for advancing a cup blank over said table and the slot therein, and a member adapted to track on the advancing cup blank to produce a crease therein.

30. In a cup forming machine the combination with a table having a slot therein, means for advancing a cup blank over the table and the slot therein, a member above the slot and co-acting therewith to track on the advancing cup blank to produce a crease therein, and means on said table for bending up a portion of the cup blank along the line of said crease.

31. In a cup forming machine the combination with a table having a slot therein, means for advancing a cup blank over the table and over said slot, a member above the table co-acting with the slot and adapted to track on the advancing cup blank to produce a crease therein, means on said table for bending up a portion of the cup blank along the line of said crease, and means acting against the bent up portion to fold the same over against the body of the blank.

32. In a cup forming machine the combination with a table, means for advancing a cup blank over the table, a member above the table adapted to track on the advancing cup blank to produce a crease therein, means on said table for bending up a portion of the cup blank along the line of said crease, means acting against the bent up portion to fold the same over against the body of the blank, a bell crank for operating said last mentioned means, and a cam for actuating said bell crank.

33. In a cup forming machine the combination with a table, means for advancing a cup blank over the table, mechanisms for applying adhesive to portions of the cup blank, mechanisms for folding over portions of the cup blank to form a flat cup, a reciprocating member, a cam mechanism for operating the same, a spring impelled member carried by said reciprocating member adapted to engage against the body portion of the flat cup to hold the same against the table, and a shoe carried by said reciprocating member adapted to engage and bend over the tip of the flat cup.

34. In a flat cup forming machine the combination with a table, of a gripper mechanism, means for operating the same to cause a cup blank to be advanced over the table, mechanisms operating on the cup blank to form a flat cup therefrom, a flat cup maga-

zine, and mechanisms connected to be operated by said operating means to receive the flat cup and deliver the same into the bottom of said magazine beneath other cups 5 already stacked therein.

35. In a flat cup forming machine the combination with a cup blank advancing mechanism, of mechanisms for forming flat cups from the blanks, a stacking magazine, 10 mechanisms for lifting the cups stacked in the magazine and then delivering cups therebeneath, and means for operating the cup

blank advancing mechanism and said cup lifting and delivering mechanisms.

36. The combination with a flat cup forming machine, of means for automatically feeding cup blanks thereto, a flat cup stacking device connected with the machine, and driving means connected to operate the forming machine, the blank feeding means 15 and the cup stacking device.

In testimony whereof I have hereunto subscribed my name.

CESARE BARBIERI.
